UNITED STATES PATENT OFFICE.

FREDERICK RICHARD SIMMS, OF KILBURN, LONDON, ENGLAND, ASSIGNOR TO SIMMS
MAGNETO COMPANY, OF NEW YORK, N. Y.

MAGNETO-ELECTRIC MACHINE.

1,039,454.

Specification of Letters Patent. Patented Sept. 24, 1912.

Application filed October 9, 1911. Serial No. 653,539.

To all whom it may concern:

Be it known that I, FREDERICK R. SIMMS, a subject of the King of Great Britain, residing at Wilbeck Works, Kimberley Road, 5 Willesden Lane, Kilburn, London, England, have invented certain new and useful Improvements in Magneto-Electric Machines; and I do hereby declare the following to be a full, clear, and exact description of the 10 invention, such as will enable others skilled in the art to which it appertains to make and use the same.

This invention consists in the novel features hereinafter described, reference being 15 had to the accompanying drawings which illustrate an embodiment of the invention which I have selected for the purpose of illustrating the same and the said invention is fully disclosed in the following description and claims.

Referring to the drawings, Figure 1 represents a vertical longitudinal sectional view of a high tension magneto electric machine embodying my present invention. Fig. 2 is 25 an end elevation of the same. Fig. 3 is a partial end elevation with the commutator removed. Fig. 4 is a plan view of the commutator detached. Figs. 5 and 6 are sectional views on the lines 5-5 and 6-6 of Fig. 4 respectively. Fig. 7 is a diagrammatic representation of the circuits, showing 30 the switch in the " accumulator" position.

This invention relates to high tension magneto electric machines intended for use especially in a dual ignition system in which a battery or accumulator is employed for the purpose of energizing the primary winding of the armature of the high tension magneto electric machine when the magneto is 35 not in operation, the armature acting in such case as an induction coil and enabling the igniting sparks to be produced by interrupting the primary current by means of an automatic trembler and distributing the high 40 tension current produced in the secondary winding to the ignition plugs in the usual manner, a suitable switch being provided for closing the circuit through the magneto alone or through the battery and trembler, 45 said switch having also an " off " position in which the battery is cut out of action and the magneto is " earthed " in the usual way.

My present invention addresses itself particularly to the provision in a magneto of

the kind just described of a commutator, the 55 construction and operation of which is hereinafter more fully described.

In order that my invention may be fully understood, I have selected for purposes of illustration an embodiment of the same consisting of a magneto electric machine of the well known Simms high tension type containing my present invention.

In the accompanying drawings, 1 represents the permanent magnets, 2 the armature 65 comprising the primary and secondary coils and 3 is the high tension terminal of the collecting brush holder 4.

5 is the distributor provided with terminals *a*, *b*, *c* and *d* for distributing the high 70 tension current to the various spark plugs.

One end of the low tension or primary winding of the armature is connected to the armature core, and thus to the frame of the magneto, and the other end is led through 75 the hollow spindle of the armature to a contact breaker carried at one end of the armature shaft and is connected to a fixed part of the contact breaker, to wit, a metal block 6, see Fig. 3 which is secured to but insulated 80 from the supporting disk 7, which forms the main body of the contact breaker. The block 6 is provided with a platinum pointed screw 8 and a bell crank lever 9 carries a second platinum pointed screw 10 adapted 85 to make contact at the proper time with the screw or contact 8. The bell crank lever 9 is pivotally mounted on the disk 7 and is electrically connected to the frame of the magneto. The bell crank lever 9 is also provided with a fiber heel 11 which is adapted to engage two segmental surfaces 12, 12 on the inner peripheral face of a ring 13 surrounding the contact breaker and secured to or forming part of an annular casing 14 95 revolvably mounted with respect to the frame of the magneto and to which is connected the timing lever 15. The segmental surfaces are separated by recesses 16, 16 into which the fiber heel 11 may extend, thus permitting 100 the contacts 8 and 10 to come together and said contacts are separated and held separated whenever the fiber heel 11 is in engagement with either of the segmental surfaces 12, 12.

This sudden interruption of 105 the primary or low tension circuit induces a current of high potential in the secondary or high tension circuit, producing a flaming

spark of great heat at the points of each of the sparking plugs in turn through the action of the distributor.

The parts hereinbefore described are the usual parts of a high tension electric magneto of the Simms type and do not in themselves form part of my present invention.

The contact breaker is provided with a pair of brushes for engaging the commutator hereinafter described, one of said brushes being carried by the block 6 and the other by the disk 7, said brushes being arranged in diametrically opposite positions with respect to the axis of said disk. In the present instance each brush consists of a cylindrical block or carbon 17 and 18 respectively the brush 17 fitting in a cylindrical casing secured to the block 6 and the brush 18 being similarly mounted in a casing on the disk 7, said brushes being provided with the usual pressure springs located in said casings in rear of the brushes.

The annular casing 14 is provided with a cover containing the commutator, said cover comprising a metal ring 20, see Figs. 4, 5 and 6 and Fig. 1, closed by a circular body 21 of insulated material fitted therein. On the inner face of said insulated material, a flat metal annular plate, preferably of brass, is embedded in and supported by the insulating material and said metal plate is then sawed in two directions across the center, thus dividing it into four pieces which are permanently secured to the insulating material and have their inner faces in the same plane. Two of these segments are connected to the battery or accumulator or other extraneous source of current and the remaining two are not connected.

In the drawings 22, 23, 24 and 25 represent the segments of the commutator, of which segments 22 and 24 are provided with binding posts 22^a and 24^a respectively. While the commutator may be formed by providing a ring of greater thickness than required, which ring is first sawed partially through and then embedded in the insulating material 21, the solid portion of the ring is then cut away leaving the separate segments separated by the saw cuts indicated at 26, Fig. 4, which are only wide enough for good insulation. This method of construction insures the faces of the segments which engage the brushes 17 and 18, being in the same plane. Moreover by providing the disconnected segments 23 and 25 between the connected segments 22 and 24 the brushes will always rub over the same metallic material during the rotation of the armature and all the brush engaging portions of the commutator will wear evenly, which is not the case where the brushes pass from a metal segment over intervening portions of other material. The saw cuts being so narrow, the brushes which are of considerably greater

width readily bridge over the same, thus making the operation of the commutator as noiseless and frictionless as possible. The length of the connected segments 22 and 24 and their arrangement in the commutator is such that current can only pass from the battery through the primary coil of the armature when the contact breaker points 8 and 10 are separated, as these points are in parallel with the commutator segments and consequently contact between them would short circuit the commutator segment and cause an excessive current through the accumulator due to decreased resistance in the circuit. This necessitates a considerable length of insulation between the segments 22 and 24 which is supplied by the insulated and non-connected segments 23 and 25. The position of the commutator with respect to the casing 14, is determined by any desired means. In this instance a pin is provided on one of said parts to engage a recess in the other, said pin 14^a being shown on the casing 14, and the recess 20^a being shown in the ring 20 of the commutator.

In the center of the commutator insulating block 21 is a brush holder 27 carrying a spring actuated brush 28 which makes contact with a screw 29 passing through the contact breaker in an axial direction and securing the same to the armature spindle. The brush holder 27 projects from the exterior of the insulating block 21 and is engaged by a contact 30 on the outer end of a spring plate 31 pivotally connected at 32, to the frame of the magneto. This spring 31 serves the double purpose of securing the commutator in place, as clearly shown in Fig. 2, and also forming a connection for "earthing" the magneto.

In Fig. 7 I have illustrated diagrammatically the circuits including the controlling switch for the magneto and accumulator circuits. This switch is illustrated at 35 and for this purpose I prefer to employ the form of switch which forms the subject matter of my application for Letters Patent of the United States, Serial No. 596,638, filed Dec. 10, 1910. The switch, however, forms no part of my present invention and is only described herein for the purpose of clearness.

As indicated in Fig. 7, the switch comprises two forked contacts 36 and 37 mounted on a switch bar for joint movement, but insulated from each other. The switch is also provided with contacts 38, 39, 40, 41 and 42 and the forked contact 36 is connected with a trembler 43 which is also connected with the contact 41. With the switch in the position shown in Fig. 7, in which the accumulator is in circuit, as in starting an automobile engine, the circuit is as follows: from the accumulator by wire 50 to contact 42, through the forked contact 37 to contact

- 41, thence through the trembler to the other forked contact 36, thence to contact 38, thence by wire 51 to binding post 24^a and segment 24, thence to brush 18 and to earth, to wit, the frame of the magneto which is represented in the diagram by a dotted line; thence by wire 52 to the primary coil, thence by wire 53 (through the hollow spindle of the armature) to the block 6 of the contact breaker, thence to brush 17, thence to commutator segment 22, thence through binding post 22^a and wire 54 to the accumulator. When the contact breaker is in reverse position the position of the brushes 10 will be reversed and thus the armature will always be magnetized in the proper direction, that is first in one direction and then in the opposite direction, thus always tending to increase the magnetization of the magnets. 15
- 20 The secondary or high tension winding of the armature has one end connected with the primary or low tension winding and through this winding to earth, the other end of the secondary or high tension winding being connected to the high tension terminal 3 and thence to the distributor from which the current is distributed to the spark plugs indicated at 60, 61, 62 and 63.
- 25 By swinging the switch lever so as to bring the forked contact 36 into engagement 30 with the contacts 39 and 40, the magneto will be earthed and the accumulator circuit broken. By moving the switch still farther in the same direction, the "earthing" circuit of the magneto will be broken and the magneto circuit restored.
- 35 It will be observed that the battery ignition is timed a little later than the magneto, this being necessarily so, as otherwise the 40 contact breaker on the magneto would tend to short-circuit the self-starter just at the time when it was being brought into operation. The result, however, is that immediately after the engine has got under way 45 by virtue of the battery and coil, the magneto takes up its ordinary function, and does the work of ignition, even though other later sparks may still be caused to jump across the plugs under the immediately 50 following influence of the battery system.
- What I claim and desire to secure by Letters Patent is:—
1. In a high tension magneto electric machine for a dual ignition system, the combination with a rotary armature, of a rotary part operatively connected with said armature, a pair of brushes carried by said rotary part and electrically connected in circuit with the primary coil of the armature, a commutator provided with a plurality of metallic segments forming substantially a circle, the surfaces of said segments forming the entire brush engaging surface of the commutator, said segments being insulated 55 from each other and certain of said seg- ments only being provided with means for connecting them electrically with an exterior source of electrical energy.
  2. In a high tension magneto electric machine for a dual ignition system, the combination with a rotary armature, of a rotary part operatively connected with said armature, a pair of brushes carried by said rotary part and electrically connected in circuit with the primary coil of the armature, 70 a commutator provided with four segments arranged in a substantially complete circle and having their ends separated a shorter distance than the width of said brushes, said segments being insulated from each other, 75 and two alternate segments being provided with means for connecting them electrically with an exterior source of electrical energy.
  3. In a high tension magneto electric machine for a dual ignition system, the combination with a rotary armature, of a rotary part operatively connected therewith, two brushes carried by said rotary part and electrically connected in circuit with the primary coil of the armature, a commutator 80 comprising a block of insulating material having a metal ring connected therewith, said ring being divided into four separate segments, two only of said segments being provided with means for connecting an exterior source of electrical energy thereto.
  4. In a high tension magneto electric machine for a dual ignition system, the combination with a rotary armature, the primary coil of which has one end connected to "earth," of a rotary part operatively connected with the armature, two brushes carried by said rotary part, one of said brushes being connected to the primary coil, and the other to "earth," a commutator 100 provided with contact segments adapted to be connected in circuit with the poles of an accumulator, and provided with a brush holder and brush engaging a portion of said rotary part connected with the primary coil, 105 and a detachable arm connected with the frame of the magneto and detachably engaging said commutator brush holder, for "earthing" the magneto.
  5. In a high tension magneto electric machine for a dual ignition system, the combination with the rotary armature, of a rotary circuit breaker connected therewith and provided with a fixed and a movable contact in circuit with the primary coil of the 115 armature and means for operating said movable contact as the contact breaker is rotated, two brushes carried by said contact breaker, one of which is electrically connected with each of said contacts, a commutator provided with brush engaging contacts in circuit with an exterior source of electrical energy, said brush contacts being so located with respect to the means for operating the 120 movable contact of the circuit breaker, as 125
  6. In a high tension magneto electric machine for a dual ignition system, the combination with the rotary armature, of a rotary circuit breaker connected therewith and provided with a fixed and a movable contact in circuit with the primary coil of the 130 armature and means for operating said movable contact of the circuit breaker, as

- to make contact with said brushes when the contacts of the contact breaker are open, said brush engaging contacts being insulated from each other and widely separated.
5. In a high tension magneto electric machine for a dual ignition system, the combination with the rotating armature, of a rotary circuit breaker connected therewith, and provided with a fixed and a movable 10 contact, in circuit with the primary winding of the armature, a casing movable in a rotary direction provided with means for operating the movable contact, a timing lever connected with said casing, brushes carried by said contact breaker, and connected in circuit with the primary winding of the armature, a commutator provided with separated contacts for engaging said brushes, said contacts being provided with means for connecting them to an external source of electrical energy, means for connecting said commutator with the timing lever casing, for movement therewith.
20. 6. In a high tension magneto electric machine for a dual ignition system, the combination with the rotating armature, of a rotary circuit breaker connected therewith, and provided with a fixed and a movable contact, in circuit with the primary winding 25 of the armature, a casing movable in a rotary direction provided with means for operating the movable contact, a timing lever connected with said casing, brushes carried by said contact breaker, and connected in circuit with the primary winding of the armature, a commutator provided with separated contacts for engaging said brushes, said contacts being provided with means for connecting them to an external source of electrical energy, means for connecting said commutator with the timing lever casing, for movement therewith.
30. 7. In a high tension magneto electric machine for a dual ignition system, the combination with the rotating armature, of a rotary circuit breaker connected therewith, and provided with a fixed and a movable contact, in circuit with the primary winding 35 of the armature, a casing movable in a rotary direction provided with means for operating the movable contact, a timing lever connected with said casing, brushes carried by said contact breaker, and connected in circuit with the primary winding of the armature, a detachable commutator provided with separated contacts for engaging said brushes, means for connecting said contacts with an external source of electrical energy, means for detachably securing said

commutator to the timing lever casing, and interlocking devices on said casing and commutator for determining the relative positions thereof.

8. In a high tension magneto electric machine for a dual ignition system, the combination with the rotating armature, of a rotary circuit breaker connected therewith, and provided with a fixed and a movable contact, in circuit with the primary winding 45 of the armature, a casing movable in a rotary direction provided with means for operating the movable contact, a timing lever connected with said casing, brushes carried by said contact breaker, and connected in circuit with the primary winding of the armature, a detachable commutator forming the cover for the timing lever casing, and inclosing said contact breaker, said commutator being provided with brush engaging 50 contacts insulated from each other and so located as to make contact with said brushes only when the contacts of the contact breaker are separated, a brush holder and brush mounted in said commutator, said brush engaging a part on said contact breaker connected with the primary winding and said brush holder having a part extending to the exterior of the commutator and an arm secured to and connected electrically with the magneto frame, and having a part at its outer end to engage said brush holder, to make contact therewith and to hold the commutator in position.

In testimony whereof I affix my signature, 75
in the presence of two witnesses.
